AMMUNITION STORAGE BOX

Ormund A. Kravik, White Bear Lake, Minn., assignor to Nobles Engineering Company, St. Paul, Minn., a corporation of Minnesota

Application March 28, 1955, Serial No. 497,129

6 Claims. (Cl. 89—34)

This invention relates to an improvement in ammunition storage boxes and deals particularly with a box for containing a series of connected shells to be delivered to a gun through a flexible chute.

Considerable difficulty has been experienced in providing a storage box for shells connected in chains so that they may be delivered in sequence to a high speed gun. If these shells are folded in layers within the ammunition box the harness or links connecting the shells have a tendency to catch or engage one another so that the chain does not feed smoothly from the box. The present invention, while useful for other purposes, is particularly useful in supporting interconnected shells so that they may be quickly and easily withdrawn from the ammunition box and fed through the box outlet into the flexible chute leading to the gun.

A feature of the present invention resides in the provision of a box having a series of upright partitions between which the connected shells may be festooned. The partitions are normally spaced apart a distance only slightly greater than the combined diameters of the two rows of shells festooned between each pair of partitions so that the ammunition box can be maintained at a minimum size to accommodate the shells. The structure is such that as a pull is exerted upon the series of connected shells, first one partition and then the next is permitted to fold forwardly so that the shells can be easily drawn from the box with a minimum of friction.

A further feature of the present invention lies in the provision of an ammunition box having a series of parallel partitions which are hingedly supported to fold forwardly in sequence as the shells are withdrawn. Each partition is held in upright position until the shells between this partition and the next forward partition have been withdrawn. However, as soon as one festoon of shells has been removed the next partition may pivot forwardly so that the shells festooned behind this partition may be withdrawn with a minimum of friction.

A feature of the present invention resides in the provision of an ammunition box having a series of partition walls hingedly connected in parallel spaced relation to a bottom surface of the box and having a novel means of normally holding the partition in an upright position. A latch plate is hingedly connected to the forward side of each partition wall and this plate includes laterally projecting cam rollers or guides engaging in suitable cams on the side walls of the box. The plate is normally held against the partition wall to which it is attached by the shells lying forwardly of this wall. When the shells holding the latch plate against its partition are removed, the latch plate can pivot forwardly and upwardly so that the cam rollers become disengaged from their cams and permitting the partition wall to swing forwardly.

A further feature of the present invention lies in the fact that the ammunition box functions effectively even while inverted as in the event of inverted flight. Conventional ammunition boxes store the ammunition in horizontal layers on the bottom of the box. When

2

partially empty, the ammunition is agitated and tossed about when the aircraft is flown in an inverted position or is flown in maneuvers where the direction of flight is suddenly changed. This causes interlocking of the belt links and resultant jams, stopping the gun. In the present box, the ammunition is held in a restrained position until the gun pulls it from the box, thus obviating these previous difficulties.

Another feature of the present invention lies in the fact that as each partition falls forwardly, it forms a smooth path over which the ammunition may ride as it moves toward the box outlet.

These and other objects and novel features of my invention will be more clearly and fully set forth in the following specification and claims.

In the drawings forming a part of the specification: Figure 1 is a front elevational view of an ammunition box showing the general form thereof.

Figure 2 is a sectional view through a portion of the box, the section being parallel to the box end illustrated in Figure 1.

Figure 3 is an enlarged sectional detail showing the manner in which a latch plate is connected to its partition wall.

Figure 4 is a top plan view of a portion of the ammunition box shown in Figure 1.

Figure 5 is a sectional view through one of the partition walls.

Figure 6 is a side elevational view of the ammunition box, a portion of the box being shown in section.

Figure 7 is a sectional view showing the interior of the ammunition box after a number of the shells have been removed therefrom.

The particular shape and design of the ammunition box is not of utmost importance. In the particular form illustrated the box includes a front wall 10, a rear wall 11 and a bottom wall 12. Side walls 13 and 14 are provided on opposite sides of the body and a top wall 15 normally closes the top of the box. At the juncture between the front wall 10 and the top wall 15 an adapter 16 is provided which is designed to connect the ammunition box to a flexible chute which is not illustrated in the drawings. The flexible chute normally connects the ammunition box A with a gun of suitable type.

As is indicated in Figures 6 and 7 of the drawings, a series of partition walls 17 are hingedly connected at their lower edges by hinges 19 to the bottom wall 12. These hinges 19 permit the individual partitions 17 to fold forwardly toward the front wall 10 as is indicated in Figure 7 of the drawings. In storage position, however, the partition walls are parallel and upright as is indicated in Figure 6 of the drawings.

Each of the partition walls 17 is provided with a latch plate 20 hingedly connected thereto by means of a hinge connection 21 extending laterally of the partition wall 17 and parallel to the axis of each hinge 19. As is indicated in Figure 3 of the drawings, hinge bearings 21 may be connected to the partition wall and the upper edge of each latch plate 20 is provided with spaced aligned bearings 22. A hinge pivot 23 extends through the bearings 21 and 22 which are alternated through the width of the partition members 17 to provide the hinge connection. The latch plate 20 is provided at each lateral edge with a forwardly extending flange or finger 24 designed to support a cam pin or roller 25. Each pin 25 extends laterally beyond the latch plate 20, each latch plate being provided with two oppositely projecting pins or rollers designed to engage in suitable cam grooves formed in the side walls of the box.

With reference to Figure 3 of the drawings, it will be noted that each side wall such as 13 includes a bottom portion 26 connected by an off set 27 to an intermediate

portion 29. The intermediate wall portion 29 is connected by an off set 30 to an upper wall portion 31. The wall portions 26, 29 and 31 are parallel but off set, the lower wall portions 26 being spaced apart a greater distance than the intermediate wall portions 29 and the intermediate wall portions 29 being spaced apart a distance greater than the upper wall portions 31.

As a result an ammunition box is formed which is wider in its lower portion than in its upper portion. The lower wall portions 26 are spaced apart a distance sufficient to accommodate the cam pins or rollers 25 therebetween. However, the intermediate wall portions 29 are normally too close together to accommodate the rollers or pins 25 therebetween, but this intermediate wall portion on each side of the box is provided with a series of opposed cam slots which are, in effect, outwardly bulging portions of proper depth to accommodate the pins or rollers 25.

From an examination of Figures 6 and 7 of the drawings, it should be obvious that each cam slot has a blind end 32 which is connected by a forwardly and upwardly inclined slot portion 33 to a top curve portion 34. This top curve portion 34 leads to a downwardly and forwardly flared outlet portion 35. Each of the cam slots is similarly shaped and there are a pair of opposed cam slots for each partition to accommodate the laterally projecting pins or rollers of the corresponding latch plate.

With reference now to Figure 7 of the drawings, it will be seen that when a latch plate 20 is in vertical position against the partition wall to which it is hinged, the cam pins or projections engage in the blind ends 32 of the cam slots, thus holding the partition walls from pivoting in either direction. However, if the latch plate 20 is permitted to swing forwardly as is illustrated in Figure 7, the cam pins or rollers can ride up in the upwardly inclined portions 33 of the slot, around the top curved portion 34, and leave the cam slot through the flared outlet 35. The partition 17 is then free to swing forwardly against the next forward partition in the manner shown at the right side of Figure 7.

Having now described the construction of the ammunition box, the operation will be described. The top of the box is normally opened in any suitable way for the loading operation. The end of the series of connected shells is fed downwardly between the partition wall 17 at the extreme left end of the box as viewed in Figure 7. This partition is in its vertical position and the chain of shells is lowered into the area between the first and second partitions to form a festoon. When the festoon of shells is formed, the shells bear against the latch plate of the first partition member and hold this plate from pivoting upwardly and forwardly thus locking the partition in vertical position. A festoon of shells is then formed between the second and third partitions, this festoon holding the locking plate of the second partition wall from swinging forwardly. The weight of the latch plate tends to hold each partition in an upright position unless there is a forward pull exerted upon the upper edge of the partition. Thus little difficulty is found in festooning the shells between the partitions and the same procedure is followed until the box is filled. The end of the chain of shells extends through the adapter 16 and through the flexible chute to the gun.

When the gun is operated, a pull is exerted upon the chain of shells, pulling the festoon of shells between the foremost partition panel and the end wall 10 through the adapter 16. When these shells have been withdrawn, a forward pull is exerted on the upper extremity of the foremost partition wall. This forward partition wall is unlocked in upright position and immediately falls forwardly so that its upper edge rests against the front wall 10 of the box.

The second festoon of shells is then drawn from the box until a forward pull is exerted upon the upper end

of the second partition wall. By this time the shells between the first and second partitions have uncovered the latch plate 20 and this latch plate swings forwardly and upwardly, the cam pins or rollers connected thereto sliding in the corresponding cam slot. This unlocks the second partition and this partition may then fall forwardly against the first partition. In the same manner each partition falls forwardly when the latch plate thereon is uncovered and a forward pull is exerted upon the top of the partition. When all of the partitions have swung forwardly the last of the chain may be drawn from the box, the partitions forming a relatively smooth surface offering no obstructions to the movement of the shells.

In actual tests the present ammunition box has been found to function effectively even when the shells are removed at an extremely high rate of speed. Due to the fact that the clips holding the shells in a chain normally include certain projecting parts, there has always been some difficulty due to the cartridge clips hooking together to prevent a smooth movement of the cartridge chain. Furthermore, as the cartridge clips are usually centrally connected by ring-shaped links and as the projectile ends of the cartridges are smaller than the other ends, there has always been a tendency for the cartridges to stack improperly and to twist and turn as they are moved. With the present arrangement each festoon of shells may be easily withdrawn with virtually no chance of twisting or binding, thus greatly decreasing the chance that the cartridges will catch or jam in transit.

In accordance with the patent statutes, I have described the principles of construction and operation of my ammunition storage box, and while I have endeavored to set forth the best embodiment thereof, I desire to have it understood that obvious changes may be made within the scope of the following claims without departing from the spirit of my invention.

I claim:

1. A box for containing an elongated chain of connected elements, the box including a box body having an outlet at one end thereof and a pair of spaced parallel side walls, each side wall being formed with a series of upwardly curving arcuate slots closed at one lower end and open at the other lower end, each side wall being offset below the open ends of said slots to thereby increase the lateral spacing of the walls beneath said slots, a series of upright partitions hingedly connected to the bottom of the box, said partitions being spaced to permit a loop of the chain to be festooned between the pairs of adjacent partitions and said partitions being swingable toward said outlet, a latch plate hinged adjacent its upper edge to the side of each partition facing said outlet, each plate carrying a pair of integral fingers at each side thereof directed toward said outlet and provided with an outwardly issuing pin at the free end of each finger, each pin having a length sufficient to project into one of said slots but short enough to permit the pins to be released from said slots via the open ends thereof without interference from said wall portions beneath the slots, whereby pressure of a chain element against any one of said latch plates holds that latch plate and its pins adjacent the closed ends of their associated slots and hence the partition to which that particular latch plate is hinged in an upright position until said chain element is removed.

2. A box for containing an elongated chain of connected elements, the box including a box body having an outlet at one end thereof and a pair of spaced parallel side walls, at least one of said side walls including a portion spaced from the bottom of the box which is inwardly offset from the lower portion of said wall, said inwardly offset portion including a series of cam slots open at one end to the lower extremity of said offset portion, a series of upright partitions hingedly connected to the bottom of the box, said partitions being spaced to permit a loop of the chain to be festooned between the pairs of adjacent

partitions, a latch plate hinged adjacent an edge to the side of each partition plate facing said outlet, a cam pin mounted on each plate and engageable in a corresponding cam slot, each said plate, when hinged against its partition, holding said pin engaged in its cam slot, pivotal movement of each said plate away from its partition permitting said cam pin to move from the open end of said cam slot, said cam pins being freely movable between the lower portions of said side walls in any position of said plate, whereby pressure of a chain element against any said plate holds said plate against its partition and said plate holds the cam pin thereon from disengagement from its cam slot.

3. The structure of claim 2 and in which said cam slots comprised upwardly curved slots having a closed end opposite said open end, and in which said plates are pivoted along their upper edges.

4. The structure of claim 2 and in which pressure in a direction toward said outlet acting against the upper edge of any of said partitions will pivot the plate mounted on the partition away from the partition in the absence of pressure of a chain element against this plate.

5. A box for containing an elongated chain of connected elements, the box including a box body having an outlet at one end thereof, a series of upright partitions hingedly connected to the bottom of the box, said

5

10

15

20

25

partitions being spaced to permit a loop of the chain to be festooned between the pairs of adjacent partitions, said partitions being swingable toward said outlet, and locking means for holding said partitions upright, said locking means including a latch plate hinged to each partition and normally held against its partition and thus in locked position by the loop of chain festooned between the pairs of partitions, the elimination of each loop releasing the corresponding locked means to permit a corresponding partition to hinge forwardly toward said outlet, each said latch plate including laterally extending means extending beyond the corresponding partition, said locking means also including cooperable means on a wall of said box body engaged by said laterally extending means when said latch plate is against its partition and disengageable therefrom when said latch plate hinges forwardly toward said outlet.

6. The structure of claim 5 and in which said cooperative means comprises cam means formed on a side wall of said box body.
